UNITED STATES PATENT OFFICE.

WILLIAM E. CLEVELAND, OF MEDFORD, MASSACHUSETTS.

STEAM BOILER AND METHOD OF MAKING THE SAME.

1,420,182.

Specification of Letters Patent. Patented June 20, 1922.

Application filed September 27, 1919. Serial No. 327,008.

To all whom it may concern:

Be it known that I, WILLIAM E. CLEVELAND, a citizen of the United States, residing at Medford, in the county of Middlesex 5 and State of Massachusetts, have invented certain new and useful Improvements in Steam Boilers and Methods of Making the Same; and I do hereby declare the following to be a full, clear, and exact description 10 of the invention such as will enable others skilled in the art to which it appertains to make and use the same.

The present invention relates to the manufacture of steam boilers and more particularly to steel fire-tube boilers for steam automobile engines and methods of making the same.

The primary object of the present invention is to provide a novel and improved 20 method of constructing a boiler for steam automobile engines to the end that the boiler produced by practicing this method shall be stronger, more durable and less expensive to manufacture than boilers of this type 25 heretofore produced.

With this and other objects in view, the several features of the present invention will be clearly understood from the following description and accompanying drawings, in 30 which Figure 1 is a side elevation, partly in section, of a fire-tube boiler constructed in accordance with the improved method; Fig. 2 is an enlarged vertical sectional view of the lower end of a stiffening rod and a 35 portion of the bottom head of the boiler to which the rod is secured; Fig. 3 is an enlarged vertical sectional view of the lower end of one of the fire-tubes and a portion of the bottom head of the boiler to which 40 the tube is secured; Fig. 4 is a view similar to Fig. 3 but with the bottom head shown before the fire-tubes are applied; Fig. 5 is a similar view showing a fire-tube applied but without being secured in place; and Fig. 45 6 is a sectional plan view taken on the line 6—6 of Fig. 5.

The boiler illustrated in the drawings comprises a seamless cylindrical shell 2 of steel which is reenforced by suitable reenforcing bands 4. The ends of the shell are closed by top and bottom heads 6 and 8, respectively, comprising circular plates having peripheral flanges 10 which closely fit over and are welded to the ends of the shell. 55 The flanges 10 are also welded to the reenforcing bands 4 located adjacent the outer

ends of the shell as indicated in Figs. 1 and 3. The outer edges of the ends of the shell are bevelled to provide annular spaces 12 between the ends of the shell and the heads. 60 The lower end of the shell is provided with a plurality of transverse radial slots 14 leading from the space 12.

The heads are connected by fire-tubes 16 of the usual construction, the ends of which 65 tubes extend through apertures in the heads. The apertures in the top head throughout their length are of the same diameter as the tubes, while the apertures in the bottom head have a cylindrical lower portion 18 of 70 the same diameter as the tubes, and an enlarged cylindrical upper portion 20, the upper end of which is countersunk or flares outwardly. The lower ends of the tubes are flared slightly and the tubes are inserted 75 through the apertures in the bottom head after this head is applied to the shell but before the top head is applied (Fig. 5), the tubes then being held in position by any suitable means as by a jig engaging their 80 upper ends. Ferrules 21 of the usual construction may be applied to the lower ends of the tubes. The bottom head is then heated to approximately 1700 degrees Fahrenheit, whereupon a suitable welding or brazing 85 material in a molten state is poured upon the inside surface of the bottom head. This brazing material is supplied in sufficient quantity to fill the spaces between the upper portions of the walls of the apertures and 90 the tubes, and to flow through the slots 14 to fill the annular space 12. By this method it will be seen that the brazing material surrounds the tubes well down into the apertures so that when the brazing material so 95 solidifies, the tubes are uniformly and effectively sealed and securely held in the apertures. Moreover, the lodgement of the brazing material in the annular space 12 provides a uniformly tight joint between the 100 lower end of the shell and the bottom head 8.

When the brazing material has become thoroughly set, the top head is welded upon the upper end of the shell and the upper ends of the tubes are welded or swaged over 105 in the usual manner.

The top and bottom heads are provided with central apertures 24 (Fig. 2), having an enlarged outer portion which flares outwardly. The apertures receive the ends of 110 a stiffening rod 26 having an annular groove 28 at each end. After the stiffening rod

is applied, it is secured in place by means of welding material which is caused to fill the space between the ends of the rod and the outer portion of the walls of the apertures, and then the extreme ends of the rod are headed over. This manner of securing the stiffening rod to the heads provides a tight and strong joint.

Having thus described the invention, 10 what is claimed is:

1. The method of constructing a fire-tube boiler which comprises forming a cylindrical shell, bevelling the outer edge of one end of the shell, forming a transverse slot 15 in said end of the shell, closing said end of the shell by means of a head comprising a plate having an annular flange engaging the cylindrical wall of the shell, forming a plurality of apertures in the head to receive 20 the ends of the fire tubes, inserting one end of the fire tubes in the apertures, and applying brazing material to the inner surface of the head so that it will flow through said slot in the end of the shell and into the 25 space between said bevelled outer edge of the end of the shell and the bottom head and flow about the tubes so as to seal the joints between the tubes and head.
2. A fire-tube boiler having, in combination, 30 a cylindrical shell having the outer edge of one end thereof bevelled, a head closing said end of the shell comprising a

plate having a plurality of apertures therein and having an annular flange engaging the cylindrical wall of the shell, fire-tubes 35 having one end inserted in the apertures in the plate, and brazing material applied to the inner surface of the head and in the space between the bevelled edge of the shell and the head.

3. A fire-tube boiler having, in combination, a cylindrical shell having the outer edge of one end thereof bevelled and having a transverse slot in said end, a head closing said end of the shell comprising a plate 45 having a plurality of apertures therein and having an annular flange engaging the cylindrical wall of the shell, fire-tubes having one end inserted in the apertures, and brazing material applied to the inner surface of the head to seal the joint between the fire-tubes and said plate and to seal the joint between the shell and the head.

4. A fire tube boiler having, in combination, a shell provided with a head having 55 a series of apertures therein having their inner portions countersunk, fire tubes having one end inserted in the apertures, and brazing material applied to the inner surface of the head and filling the space between the walls of the countersunk portions of the apertures and the fire tubes to 60 secure the tubes to the head.

WILLIAM E. CLEVELAND.
